CLAIM

The ornamental design for a teether, substantially as shown and described.

DESCRIPTION

FIG. 1 is a bottom, front, right perspective view of a teether, showing my new design;

FIG. 2 is a front elevation view thereof;

FIG. 3 is a back elevation view thereof;

FIG. 4 is a top plan view thereof;

FIG. 5 is a bottom plan view thereof;

FIG. 6 is a right side elevation view thereof; and,

FIG. 7 is a left side elevation view thereof.

The broken lines in FIG. 3 depict portions of the teether that form no part of the claimed design.
